UNITED STATES PATENT OFFICE

CARROLL B. COLLINS, OF PITTSBURGH, PENNSYLVANIA, ASSIGNOR TO THE KOPPERS COMPANY, A CORPORATION OF DELAWARE

GAS PURIFICATION APPARATUS

Application filed May 2, 1929. Serial No. 359,737.

This invention relates to gas purification and cooling apparatus and more particularly to the gas inlet located at the bottom of a producer gas purifier and cooler.

5 In apparatus as previously constructed, gas has been led from a plurality of producers through an equal number of waste heat boilers to a single cooler or purifier.

The gas leaving the waste heat boilers was 10 carried into a common gas header from which it was piped to the gas coolers. It was necessary to provide this long horizontal gas header with dust legs or clean-out pipes to remove the dust that settled 15 out of the gas. It was also necessary to provide one mushroom valve for each boiler.

In a gas purifier and cooler provided with the present invention, the gas from a plurality of adjacent waste heat boilers is delivered 20 directly to the bottom of the cooler. The bottom of the purifier is divided into a corresponding number of compartments by means of vertical partitions and each compartment is provided with a water discharge 25 connection. The gas from each waste heat boiler flows into one of the compartments at the lower part of the same.

When one of the waste heat boilers or its 30 corresponding gas producer is shut down for any reason, the water outlet for the compartment to which that waste heat boiler is connected is closed. Since a spray of cooling water is constantly falling through the baffle plates of the purifier, the water 35 in this compartment soon rises to the top of the baffle and thereby seals off gas from the boiler that is shut down. When the spray water reaches the top of the partition, it flows into the other compartments 40 from which it is drained.

In the drawings,

Figure 1 is a view, partly in side elevation and partly in vertical section, of a purifying tower embodying this invention;

45 Fig. 2 is a horizontal cross-section taken on line II—II of Fig. 1; and

Fig. 3 is a view, partly in front elevation and partly in cross-section, of the lower part of the purifying tower.

50 A purifying or cooling tower 1 is pro-

vided with the usual sprays 2 and hurdles 3. At the bottom are located two gas inlets 4 and 5 and a gas outlet 6 is located at the top of the tower. The bottom inlets are placed on opposite sides of a vertical 55 partition 7 which divides the lower portion of the tower into two compartments each capable of holding water.

The compartments are provided respectively with water outlets 8 and 9 and the 60 bottom 10 of the tower on which the partition 7 rests is inclined toward the outlets 8 and 9. There is an overflow outlet 11 located a short distance above the upper edge of the partition 7 and the tower is 65 also provided with a manhole 12.

In operation, when it is desired to shut off the gas inlet 4, for example, the valve on the water outlet 8 is closed, whereupon the water which constantly comes down 70 through the hurdles 3 from the sprays 2 fills up the compartment until the water level is even with the top of the partition 7. The water rises to a corresponding height in the vertical portion of the gas inlet 75 4, thus effectively sealing off the further passage of gas into the cooling tower from this inlet.

The water continues to descend into this compartment but is free to flow over the 80 top edge of the partition 7 and passes out through water outlet 9 along with the water which also falls on this side of the baffle plate. In a corresponding manner, the closure of the valve on outlet 9 would stop 85 the flow of gas through inlet pipe 5.

Water can flow out of overflow outlet 11 in the event that both valves 8 and 9 are closed although in ordinary operation, either the one or the other of water outlets 90 8 and 9 would be open.

This invention renders unnecessary the use of valves for gas inlets since it substitutes therefor a fluid seal or water seal. It obviates the necessity of mounting valves 95 directly on pipes of inlets 4 and 5 where they would be subjected to considerable heat and their normal operation would be interfered with by the constant accumulation of dust. This invention also renders unneces- 100

sary the placing of dust catchers at inlets 4 and 5 which would be necessary if valves were present on these lines.

While the single modification illustrated 5 shows a purifying or cooling tower with connections for two waste heat boilers only, that is, connections for two gas producers, it will be evident to anyone skilled in the art to which this invention pertains that a 10 greater number of producers could be connected to the same purifying tower by properly arranging a plurality of vertical partitions in the bottom of the tower.

Numerous other details of tower construction and arrangements of piping for shutting off a gas line by means of a water seal may be suggested by the present disclosure and yet not depart from the scope of the invention as herein claimed.

20 I claim as my invention:

1. In a scrubbing tower having a liquid spray therein, a plurality of gas inlets for the tower each having a portion thereof inclined downwardly to form a seal, the 25 seals being arranged to fill with liquid from the spray, and a liquid outlet for each seal, each seal being so arranged that when its liquid outlet is closed the water will overflow into adjacent seals.

2. In a purifying tower having a liquid spray therein, downwardly directed gas inlets, means adjacent each inlet for collecting and holding liquid from said spray to a sufficient depth to cover the respective inlets 35 and a liquid outlet for each collecting means, each collecting means being so arranged that liquid overflows into adjacent collecting means when its outlet is closed.

3. In a washing tower having a liquid spray therein, a gas inlet for said tower having a portion thereof inclined downwardly to form a seal, an outlet for the seal, the inlet being arranged to fill with liquid from the spray when the outlet is 45 closed and a second outlet for the seal into which said liquid is arranged to overflow within the tower when the first-mentioned outlet is closed.

4. In a scrubbing tower having a liquid spray therein, a downwardly directed gas inlet in the lower portion of said tower, means for collecting and retaining spray liquid to a sufficient depth to cover the inlet to constitute a seal therefor and an outlet 55 for said collecting means, said collecting means being so arranged that liquid overflows within the tower when said outlet is closed.

5. In a scrubbing tower, a liquid spray in 60 an upper portion thereof, a gas inlet pipe in a lower portion thereof, an outlet for the liquid in the bottom portion of said tower, means for closing said outlet to cause liquid to cover the end of said gas inlet 65 pipe to constitute a seal therefor, and a

second outlet for said liquid when it reaches a predetermined level in said seal.

In testimony whereof, I have hereunto subscribed my name this 29th day of April, 1929.

CARROLL B. COLLINS.
